[57] CLAIM

The ornamental design for a musket loader, as shown.

DESCRIPTION

FIG. 1 is an isometric front view of the musket loader.
FIG. 2 is both a front view and a reversed back view of the
musket loader showing the internal powder, slug and cap
compartments.

FIG. 3 is a left side view of the musket loader.

FIG. 4 is a right side view of the musket loader.

FIG. 5 is a top view of the musket loader showing the
powder spout in a typical position; and,

FIG. 6 is a bottom view of the musket loader showing the
slug and cap compartment doors each in a closed position.
